UNITED STATES PATENT OFFICE

WALTER H. SCHRAMM, OF PITTSBURGH, PENNSYLVANIA, ASSIGNOR TO WESTINGHOUSE ELECTRIC & MANUFACTURING COMPANY, A CORPORATION OF PENNSYLVANIA

SWITCH MECHANISM

Application filed May 26, 1927. Serial No. 194,248.

My invention relates to switch mechanism and particularly to disconnecting switches of the back-of-board type, wherein an insulating panel is mounted at the rear of a sheet metal switchboard and serves to support fuses and knife switches having an operating handle projecting through an opening in the switchboard.

An object of my invention is to provide a back-of-board knife switch that is assembled entirely upon an insulating base and mounted at the rear of the switchboard and having an operating handle that is also mounted upon the insulating panel in order that the switch may be assembled upon the insulating base as a unit, thereby facilitating assembly and inspection of the switch apparatus.

Another object of my invention is to provide a back-of-board type disconnecting switch having characteristics of design which enables the mounting of the insulating panel supporting switch, closer to the switchboard than is the usual custom, thus reducing the distance of the fuse receptacles mounted on the insulating base, from the front of the board, and thereby rendering its operation more safe, because it is unnecessary for the operator to reach into a deep and dark recess to replace a fuse.

Another object of my invention is to provide a back-of-board type knife switch wherein the over-all dimensions of the switch blade assembly are shortened, in order to reduce the space necessary for the safe operation of the switch.

A further object of my invention is to provide a back-of-board type disconnecting switch having the above-noted characteristics that is inexpensive to manufacture, and which may readily be assembled and installed upon the usual type of metal front switchboards.

These and other objects of my invention, that will be made apparent throughout the further description thereof, are attained by means of the switch apparatus hereinafter described and illustrated in the accompanying drawings, wherein:

Figure 1 is an elevational view of switch apparatus embodying features of my inven-

tion showing the metal front switchboard in section.

Fig. 2 is a plan view of the apparatus shown in Figure 1 with the cover removed to expose parts of the apparatus, and

Fig. 3 is an elevational view of a fragment of the switch apparatus with the insulating panel shown in section.

Referring to the drawings, the switch apparatus includes a sheet metal switchboard 4, and an insulating base or panel 5 that is attached to the switchboard 4 by brackets 6. Contact jaws 7 and pivot jaws 8 are mounted upon the panel 5, the pivot jaw 8, pivotally supporting a knife switch blade 9 that engages the contact jaw 7. Fuse receptacles or clips 11 are mounted upon the panel 5 for supporting standard cartridge fuses 12. The pivot jaws 8 and the adjacent fuse clip 11 are electrically connected by the conductor strap 13 that is secured to the insulating panel by screws 14.

A three-pole knife switch is illustrated in Fig. 2. Fig. 1 is a typical side elevation of a 2 or 4 pole switch. A pedestal 15 is mounted upon the central conductor or strap 13 between the contact jaw 8 and the fuse clip 11 on 1 or 3 pole switches, as shown in Fig. 3.

The pedestal is adapted to support the switch operating handle, to be hereinafter described, and comprises a square shaft 16 having one end extending through the panel 5 and threaded to receive nut 17 for attaching the shaft to the panel. The shaft is provided with a shoulder collar 18 which engages an insulating bushing 19 that is disposed between the collar 18 and the base 5 on 2 or 4 pole switches, or the conductive strap 13 for 1 and 3 pole switches. The threaded end of the shaft 16 is insulated from the strap 13 by an insulating bushing 21 which extends through an opening 22 in the strap 13. The bushing 21 extends into the bore 23 of the bushing 19.

By reason of the relatively wide diameter of the insulating bushing 19, the pedestal 15 is provided with a wide supporting base and therefore is rigidly mounted upon the base 5.

The operating handle 26 for the switch mechanism comprises a single bent strap 27,

of U-shape, that is disposed on opposite sides of the shaft 16 in spaced relation thereto, the bars being pivotally mounted upon the shaft 28 adjacent the center of the bars. Interlocking cams 29, the purpose of which will 5 hereinafter appear, are mounted in the spaces between straps 27 of the operating handle and on the shaft 16, the cams being secured in place by rivets 30.

10 Each switch blade 9 is provided with an insulating clip 31 that is secured thereto by rivets 32. The clips are connected for simultaneous operation by means of a metal shaft 33 that extends through holes 34 in the 15 ends of the clips. Longitudinal displacement of the shaft is prevented by cotter pins 35.

The bars 27 of the operating handle 26 are pivotally connected to the pivot shaft 20 33 by a pair of links 36, the links being disposed on the outer faces of the bars 27 and therefore clear the shaft 16 when the operating handle is moved to the open position shown in dotted lines in Fig. 2.

25 In switches of this character, it has heretofore been the practice to connect the switch blades 9 at their ends by means of an insulating bar which, in various ways, are connected to a pivoted operating handle upon the front 30 plate of the switchboard. This construction required a greater space between the front plate of the switchboard and the insulating panel, in order to accommodate the greater length of the switch blade and to provide 35 proper clearance for live parts. Switches of this character also had disadvantages in the assembly thereof, because the operating mechanism is usually mounted upon the front plate of the switchboard. In my improved switch blade apparatus, the entire 40 switch assembly is mounted upon the switch base and is independent of the cover or front switchboard.

The switchboard 4 is provided with an 45 opening 37 through which the cartridge fuse 12 is accessible. The opening is closed by a door 38 that is hinged at 39 to the switchboard 4. The operating handle 26 projects through an opening 41 in the switchboard 50 panel 4 and is provided with an insulating handle 42.

The door 38 is interlocked with the switch handle in such manner that the door cannot be opened so long as the switch is in open 55 position and the switch cannot be closed so long as the door is in open position. The interlock mechanism comprises an arcuate cam member 40 that is attached to the door 38 by means of a bolt 43. The cam is slightly 60 less in width than the space between the bars 27 of the operating handle and fits within that space when in the closed position shown in full lines in Figures 1 and 2. The cam plates 29 on the operating handle are provided 65 with arcuate cam surfaces 44 which

provide clearance for the cam 40 when the operating handle is in the open position shown in dotted lines. It will be seen that the door cannot be opened so long as the switch is in the closed position because the upper end of the cam 40 engages the convex surface 39 of the cam 29 and prevents movement of the door. The convex cam surface is of such length that it prevents movement of the door until the switch has been moved to its full open position. At this time, cam 40 will clear the cam 29 and permit opening movement of the door. However, when the cam 40 has moved to the open position, the switch cannot be closed because the concave surface 44 of the cam 29 will then engage the convex cam surface of the cam 40 and prevent closing movement of the switch so long as the door is in open position. The arrangement of the cams is such that in order to close the switch, the door must be in fully closed position.

The switch construction, above described, is relatively compact and rugged and is rendered more safe in operation by reason of the fact that the fuses 12 are disposed relatively close to the front switchboard 4.

It will be understood that the switchboard 4 is of the metal panel type and may be assembled in panels or sections which may be removed for inspection of the switch mechanism.

While I have shown and described my invention in considerable detail for the purpose of completely illustrating the same, it is my intention that the appended claims shall be as broadly construed as is permitted by the language thereof and the prior art.

I claim as my invention:

1. Switch mechanism comprising a supporting base, a switch blade member pivoted theron for movement in a plane normal to the plane of the base, a pedestal mounted upon the base and extending perpendicularly therefrom, and an operating handle comprising a forked member having portions disposed on opposite sides of the pedestal and pivoted thereto intermediate their ends, the inner ends of the said portions being pivotally connected to the said switch member.

2. Switch mechanism comprising a supporting base, a plurality of switch blade members pivoted to the base, insulating clips secured to the blade members, a bar connecting the clips for simultaneously actuating the blade members, a pair of spaced links pivotally connected to the bar, a pedestal mounted on the said base, and an operating handle comprising a pair of members disposed on opposite sides of the pedestal and pivoted thereto intermediate their ends, the inner ends thereof being pivotally connected to the spaced links in such manner

that the links may move past the pedestal when their operating handle is actuated.

3. Switch mechanism comprising a supporting base, a switch blade member pivoted thereon, an operating handle for the blade member, and a pedestal for supporting the operating handle comprising a metal shaft having a collar thereon spaced from the front face of the base, and an insulating bushing of relatively large diameter surrounding the shaft and disposed between the said collar and the supporting base, and means for drawing the collar into engagement with the bushing for securely clamping the shaft and bushing upon the base.

15 In testimony whereof, I have hereunto subscribed my name this 24th day of May, 1927.

WALTER H. SCHRAMM.
